OVERFLOW MEANS FOR RADIATORS

Joseph D. Harris, Detroit, Mich., assignor to
McCord Radiator & Mfg. Co., Detroit, Mich.,
a corporation of Michigan

Application May 1, 1933, Serial No. 668,682

13 Claims. (Cl. 220—85)

This invention relates to vent and overflow means for radiators for motor vehicles.

The general purpose and object of the invention is to provide an overflow means particularly adapted for radiators of the type having relatively shallow top tanks as made necessary by reason of the present low hood designs to prevent or reduce the loss of water through the vent tubes.

10. In radiators of this character, the top tanks have in many cases been reduced to such small capacity and are located so close to the enclosing hood and shell that venting through the filler necks as heretofore employed with deeper tanks 15 is not practical for the reason that the filler necks are so short or low to fit either under the hood or terminate substantially flush with the shell that the inlet ends of the vent tubes in the necks are so close to the water level in the tanks 20 that excessive loss of water occurs in the use of the radiators.

25. In accordance with my invention, I provide the top tank of the radiator with an overflow chamber disposed on the outer side of the tank beyond the filling opening and extending above the same whereby the inlet end of the vent or overflow tube connected with said chamber is at the highest possible point above the liquid level in the tank to prevent or reduce the loss of water from 30 the radiator due to its rise by expansion by heat from the engine or agitation or surging in the travel of the vehicle over a roadway or to the sudden stopping and starting of the vehicle or change in its momentum in the use of the so-called free wheeling devices in the vehicle drive.

35. Specifically, my invention comprises an overflow chamber on the top wall or roof sheet of the top tank and extending above the same whereby the chamber and the inlet end of the overflow tube connected therewith are so disposed above the tank that they are not easily or freely reached by the water when surging in the tank. I employ an apertured partition between the chamber and the tank to baffle the water as 40 it surges in the tank and thus prevent its free flow or entrance into the chamber to reach the vent or overflow tube for escape therethrough. The overflow chamber may be provided by a suitably shaped member applied to the top tank 45 either as a separately formed part or stamping or by pressing a portion of the tank wall upwardly to provide the chamber.

50. The invention consists further in the matters hereinafter described and claimed.

55. In the accompanying drawing:

Fig. 1 is a side view, with parts broken away and in section, respectively, of the upper part of a radiator of the type in question and its enclosing shell and hood, the radiator being provided with the overflow means of my invention; 5

Fig. 2 is a top plan view of the top tank of the radiator taken on line 2—2 of Fig. 1;

Fig. 3 is an enlarged vertical sectional view taken on line 3—3 of Fig. 2;

Fig. 4 is a similar view showing a modified 10 form of construction to be hereinafter described; and

Fig. 5 is a top plan view of the structure shown in Fig. 4, parts being broken away and in section, respectively. 15

As shown in the drawing, the radiator 1 has a core 2 and a relatively shallow top tank 3. The latter extends to the rear of the core 2 under the hood 4 of the engine, where said tank has a filling opening 5 in its top wall or roof sheet 6, 20 the filling opening 5 being under the hood when the latter is closed. The neck 7 about the opening and to which the closure cap 8 is attached, is relatively short or low as shown, to fit beneath the hood. 25

Arranged on the outer side of the top tank 3 and carried thereby is a member 9 forming an overflow chamber 10 for the radiator. Said chamber is divided from the tank by an interposed partition 11 having apertures 12 which 30 connect the chamber with the interior of the tank as shown. An overflow tube 13 is connected with the chamber 10 and leads to a discharge point at or adjacent the lower end or bottom of the radiator as in designs of this character. 35

The member 9 in the form shown in the drawing is dome-shaped and is provided on the top wall or roof sheet 6 of the tank. Member 9 extends above the tank and is preferably disposed thereon at the highest possible point above the 40 liquid level in the tank. When the top wall of the tank is arched as indicated in Figs. 1 and 2, the dome 9 is disposed at the highest point of the arch which in the design shown is midway between the ends 14, 14 of the tank. The dome 9 45 may be located adjacent the upright front wall 15 of the tank as shown in the drawing, in which case the dome is located under the outer casing or shell 16 of the radiator. Said shell in the design shown has its rear margin offset inwardly to 50 provide a seating and supporting flange 17 for the adjacent front edge of the hood 4.

The dome 9 could be arranged on the tank, as for example, adjacent its rear wall, in which case it would be disposed under the hood 4 as 55

indicated by the dotted lines *a* in Fig. 2. The location of the dome in the positions referred to is possible because the filling opening 5 is offset to one side of the transverse center line of the 5 tank. With the filling opening so located, the tank cannot be filled above the level of said opening, thereby providing a free space in the tank below the dome for the liquid in the radiator to rise due to expansion and also to surge to some 10 extent without entering the dome.

The dome as shown in Figs. 1 to 3, is made independently of the top tank as a separate stamping, afterward secured to the top wall of the tank at the place desired by solder through its marginal or base flange 18, or the dome may be pressed out of the top wall 6 of the tank to be 15 integrally connected therewith as shown at 9*a* in Figs. 4 and 5. Except for this manner of connection with the tank, the dome 9*a* is similar to 20 the dome 9 and provides an overflow chamber 10 as before.

When the dome is pressed out of the top wall of the tank, it is necessary to employ a separately formed partition member 19 which is secured as 25 by solder to the inner surface of the roof sheet 6 about the margin of the dome as indicated in Figs. 4 and 5. The partition 19 is provided with one or more apertures 20 to connect the chamber formed by the dome 9*a* with the interior of the 30 tank. Likewise, an overflow tube 13*a* is connected with the dome 9*a* and extends into the same from the exterior of the top tank so that its inlet end is at the highest possible point above the communication between the overflow chamber 35 and the interior of the tank, the same as in the previous construction. In the latter, the partition member 11 forms a part of the tank wall over which the dome shaped member is secured. The vent or overflow tube in both forms of 40 construction as stated, extends into the dome from the exterior of the tank. When the dome is located on the top wall of the tank as shown in the drawing, the tube extends into the dome above this top wall. It may be extended along 45 the front wall 15 of the tank to one of the ends 14, as shown in Figs. 1 and 2, before continuing down to the bottom or lower end of the radiator. The manner in which the tube is led to its discharge point is not material to my invention.

By the arrangement shown and described, the filling opening and its neck are not employed in 50 venting the radiator, consequently, the vent and overflow means may be positioned to extend above the top wall of the tank and the filling opening and thus be disposed at the highest point possible 55 above the liquid level in the tank to prevent or reduce the loss of water from the tank in the use of the radiator. With the venting means separate and distinct from the filling opening, the 60 vent means may be located at any desired point on the tank, either under the shell 16 as shown, or under the hood as herein described. The dome or chamber may be relatively low as indicated to fit either under the shell or the hood, and in extending above the tank and its filling opening, will effectively serve the purpose for which it is 65 desired, namely, to prevent the loss of water especially from shallow or small capacity top tanks as in the radiators required for low hood designs.

In the form of radiator shown in Figs. 1 and 2, the top tank has an inlet fitting 21 in its portion extending to the rear of the core and by which fitting the radiator is connected in the water jacket of the engine. The radiator has an 70 outlet fitting at the lower end for connection with

said jacket as in structures of this general character.

The details of construction shown and described may be variously changed and modified without departing from the spirit and scope of my invention, except as pointed out in the appended claims. 5

I claim as my invention:

1. In a radiator for motor vehicles, a top tank having a filling opening, means providing an 10 overflow chamber for the radiator on the outer side of the top tank and carried thereby, means connecting the chamber with the interior of the tank independently of said filling opening, and an overflow tube connected with said chamber- 15

2. In a radiator for motor vehicles, a top tank having a filling opening, means providing an overflow chamber for the radiator on the upper side of the top tank in offset relation to the filling 20 opening and extending above the same, means connecting the chamber with the interior of the tank independently of said filling opening, and an overflow tube connected with said chamber.

3. In a radiator for motor vehicles, a top tank 25 having a filling opening, means providing an overflow chamber for the radiator on the upper side of the top tank in offset relation to said filling opening and extending above the same, means connecting the chamber with the interior 30 of the tank independently of said filling opening, and an overflow tube connected with the chamber and extending into the same from the exterior of the tank.

4. In a radiator for motor vehicles, a top tank 35 having a filling opening in its top wall, a dome-shaped member carried by the top wall of the tank in offset relation to said filling opening and extending above the same to provide an overflow chamber for the radiator, means connecting the 40 chamber with the interior of the tank independently of the filling opening, and an overflow tube connected with said chamber.

5. In a radiator for motor vehicles, a top tank 45 having a filling opening in its top wall, a dome-shaped member carried by the top wall of the tank in offset relation to said filling opening and extending above the same to provide an overflow chamber for the radiator, a partition member between the tank and chamber and having an 50 aperture connecting the chamber with the interior of the tank independently of the filling opening, and an overflow tube connected with said chamber.

6. In a radiator for motor vehicles, a top tank 55 having a filling opening, a dome-shaped member made independently of the tank and secured thereto on its top wall in offset relation to said filling opening to provide an overflow chamber for the radiator, the portion of the top wall of 60 the tank over which the member is secured dividing the chamber from the tank and having an aperture connecting the chamber with the interior of the tank independently of the filling opening, and an overflow tube connected with 65 said chamber.

7. In a radiator for motor vehicles, a top tank having a filling opening in its top wall, a portion of said wall exterior of said filling opening being pressed upwardly to provide a dome-shaped overflow chamber for the radiator above said wall, a partition member secured to said wall and dividing the chamber from the tank, said partition having an aperture connecting the chamber with the interior of the tank independently of the 70 75

filling opening, and an overflow tube connected with said chamber.

8. In a radiator for motor vehicles, a top tank having a filling opening therein, means providing an overflow chamber on the tank and extending above the same and said opening in lateral offset relation thereto, a partition dividing the chamber from the tank and having an aperture therein connecting the chamber with the interior of the tank independently of said opening, and an overflow tube connected with said chamber.

9. In a radiator for motor vehicles, a top tank having an arch-shaped top wall having a filling opening therein to one side of the highest point of the arch, means providing an overflow chamber on said top wall at the highest point of the arch and extending above the same, a partition dividing the chamber from the tank and having an aperture therein for connecting the chamber with the interior of the tank, and an overflow tube connected with said chamber.

10. In combination, a radiator having a header provided with a filler opening, an overflow chamber communicating with the radiator interior through means other than the filler opening, said means acting to resist passage of fluid from the interior of the radiator into the chamber, and a vent conduit communicating with said chamber.

11. In combination, a radiator having a header provided with a filler opening, an overflow chamber communicating with the radiator interior through means other than the filler opening, said means being substantially coplanar with the top 5 of said header, and acting to resist the passage of fluid from the interior of the radiator into the chamber, and a vent conduit communicating with said chamber.

12. In combination, a radiator having a header 10 provided with a filler opening, an overflow chamber communicating with the radiator interior through means other than the filler opening, said means acting to resist passage of fluid from the interior of the radiator into the chamber, and a 15 vent conduit communicating with said chamber, the end of said vent conduit lying above the top of said header.

13. In a radiator having a relatively shallow top tank, a filler opening therein, and vent means 20 communicating with the tank through means other than said filler opening in the top surface of said tank whereby said tank may be completely filled without loss of cooling fluid through said vent means.

JOSEPH D. HARRIS.
